UNITED STATES PATENT OFFICE.

BERNARD H. BLANK, OF NEW YORK, N. Y., ASSIGNOR OF ONE-FOURTH TO JOSEPH L. LEVY, OF NEW YORK, N. Y.

LINING FOR REFUSE CANS.

Application filed September 27, 1923. Serial No. 665,054.

To all whom it may concern:

Be it known that I, BERNARD H. BLANK, a citizen of the United States, and a resident of the city, county, and State of New York, have invented a certain new and useful Improvement in Linings for Refuse Cans, of which the following is a specification.

This invention relates to an improvement 10 in a detachable lining for cans or other receptacles which are intended to receive garbage, ashes or other refuse, and has for its object to provide a simple article of this character which will fit the interior of the 15 receptacle snugly and lie in immediate contact therewith thereby acting to receive the contents of the can to prevent the contact of the same with the can whereby the disagreeable task of constantly cleaning the interior 20 of the can will be avoided.

A further object of this invention is to provide can linings as described above in continuous strip form, whereby the same 25 may be sold in the form of a roll from which the separate can linings may be detached and used when required.

A still further object of this invention is to provide a removable inner lining for refuse cans, which lining shall be of paper or 30 similar material and so arranged that it can be placed within cans of various size and discarded with the refuse, leaving the can clean and held out of contact with the materials placed within the same.

35 With these objects, and such other objects as may hereinafter appear, in view, I have devised the particular arrangement of parts hereinafter set forth and more particularly pointed out in the claims appended hereto.

40 Reference is to be had to the accompanying drawing, forming a part hereof, in which

Figure 1 is a plan view of one of the strips from which the linings are detached 45 and used when desired;

Figure 2 is a modified form of strip;

Figure 3 is a sectional view of a can, showing my improved lining in position within the same; and

50 Figure 4 is a perspective view of one of the linings detached from the strip shown in Figure 2 and shown in its initial position preparatory to placing it within a can.

Throughout the various views of the

drawings, similar reference characters designate similar parts.

In the embodiment of my invention disclosed in Figure 1, the elongated strip of paper or the like intended to cover the inner side walls of the can is disclosed at 1. When 60 the linings are connected in strip form the wall linings 1 are connected together by a disk of paper 2 which forms a covering for the bottom of the can.

Having found that the ordinary household garbage cans are of greater diameter than depth, the bottoms 2 are necessarily of greater diameter than the width of the wall linings 1. When the linings are sold in roll form, the initial piece on the roll is a wall 70 lining 1. This is separated from the following piece, which is a disk 2, by tearing it off on the scored or weakened line 3. The wall lining thus removed from the roll is placed within the can with its ends overlapped to the required extent to enable it to fit the can properly. The bottom disk 2 is next torn off from the roll on the scored or weakened line 4 and placed within the lining in the can and forced down to the bottom of the can.

I have found it desirable to make the bottom disk of slightly greater diameter than the bottom of the can so that when said disk is placed in position in the can it will 85 tend to flatten or straighten out and force the wall lining against the side walls of the can.

The following linings on the roll are detached and used as required in the manner 90 just explained, until the roll is exhausted.

A modified form of lining is disclosed in Figure 2, where the various linings are joined together in continuous strip form, but the bottom members are integrally connected to and form part of the wall linings. A complete lining of the character shown in Figure 2 is disclosed in Figure 4. Said lining is detached from the rest of the strip on the weakened or scored line 5, and each 100 lining consists of the wall portion 6 from the lower edges of which is the depending bottom portion 7.

To place this form of lining in position within a can, the bottom disk member 7 is folded upwardly and flat against the wall lining on the fold line 8 as indicated in Figure 4. The lining is then placed within

the can with the ends of the wall portion overlapped to the required extent. The bottom portion is then pushed down flat on the bottom of the can, such act causing it to force the wall lining against the sides of the can and hold the same in that position, as disclosed in Figure 3.

I have found it desirable to make the wall lining of a width slightly greater than the depth of the can into which it is intended to be placed whereby a portion of said wall lining will project above the top of the can and may be folded down over the upper edge of the same. In order to aid in folding down that portion of the upper edge of the wall lining which projects above the upper edge of the can, I find it desirable to slit the longitudinal edge of the wall lining at intervals as at 9. Such slits are placed in the longitudinal edge opposite to that on which the bottom disk is formed.

It will be apparent from the foregoing that many modifications of my invention may be made, one of the features of which resides in the formation of a plurality of lining blanks connected together in strip form so that the strip thus formed may be rolled up and conveniently handled and sold in such condition, and from which the linings may be removed and used as required.

When the lining disclosed in Figures 2 and 4 is rolled the bottom disk 7 is folded over flat against the wall lining as disclosed in Figure 4. It will also be apparent that in the embodiment of my invention as disclosed in Figures 2 and 4, the bottom disk may not necessarily be located at a central point on one of the longitudinal edges of the wall lining, but at any suitable point thereon.

From the foregoing, it is obvious that my invention is not to be restricted to the several embodiments herein shown and described, but is broad enough to cover all structures coming within the scope of the annexed claims.

Having described my invention, what I claim is:

1. An article of the class described com-

prising a continuous strip of paper consisting of elongated sections adapted to form wall linings for the interior of a can, said sections being connected to and spaced by substantially circular sections adapted to form bottom linings for a can, all of the sections being adapted to be detached from one another.

2. An article of the class described comprising a continuous strip of paper divided by lines of scoring into a plurality of sections intended to be detached from one another and used as linings for the wall of a can, and substantially disk-shaped members connected to said sections and intended to be used for bottom linings in co-operation with said wall linings.

3. An article of the class described comprising a continuous strip having a plurality of sections divided by weakened lines on which said sections may be separated from each other, some of said sections being shaped to fit and cover the inner sides of the wall of a receptacle, and other of said sections being adapted to fit the bottom of a receptacle, said wall sections each being provided with a plurality of slits extending inwardly from one of their edges.

4. An article of the class described comprising a strip composed of a plurality of sections shaped to fit the side walls of a can, circular sections interposed between said wall sections, said circular sections being of greater diameter than the width of said wall sections, and weakened lines separating the various sections.

5. An article of the class described comprising a can lining consisting of an elongated strip of paper adapted to cover the inner face of the side wall of the can, and a section of greater diameter than the width of said strip, adapted to cover the bottom of the can.

Signed at the city, county and State of New York, this 26th day of September, 1923.

BERNARD H. BLANK.
